UNITED STATES PATENT OFFICE

2,463,343

LOCKING CENTER PIN FOR RAILWAY CARS

Keith Williams, Buffalo, N. Y.

Application July 4, 1945, Serial No. 603,135

7 Claims. (Cl. 105—200)

1

My invention relates to improved locking center pin means for railway cars.

One of the objects of my invention is to provide a one-piece center pin for railway cars, together with positive locking means for the center pin, to prevent the displacement of the center pin and the separation of the car body and truck during operation.

A further object is to facilitate the assembly and disassembly of the car body and truck by the provision of a structure in which the center pin can be conveniently and readily applied from the upper side of the truck bolster and the under side of the body bolster and then locked.

Other objects of the invention will appear from the following description and claims in connection with the accompanying drawings which illustrate one embodiment of the invention.

Referring to the accompanying drawings.

Fig. 1 is a central vertical section transversely of the car through the body bolster and truck bolster, and illustrating the locking center pin in position;

Fig. 2 is a horizontal section on the line 2—2 of Fig. 1;

Fig. 3 is a vertical section of that portion of the truck bolster shown in Fig. 1, and illustrating the center pin inserted from above and before it is rotated into locking position;

Fig. 4 is a top plan view of the structure shown in Fig. 3, with the intermediate flange partly broken away to illustrate the locking lugs;

Fig. 5 is a sectional view similar to Fig. 1, but illustrating a modification of the center pin and bolster structure to provide additional locking means for the pin;

Fig. 6 is a plan view of the center plate used in connection with the modification shown in Fig. 5; and

Fig. 7 is a vertical sectional view of the truck bolster and locking pin, and illustrating another modification of the locking means.

This invention involves center pin means for the rotative connection between the car body and the truck of railway cars. In the drawings, the car body is represented by the body bolster A, and the truck by the bolster B, sufficient of these parts being shown to illustrate the invention. The center sill 1 of the car body has the usual center filler 2 for the center pin, and two diaphragm members 3, making up the body bolster. The center filler and center sill bear upon a center plate 5 which in turn is seated in an annular recessed bearing 6 on the upper side of the truck bolster B. The center filler has a center bore 7

2

in which the center pin C is positioned. Likewise, the truck bolster has a space or bore 8 for the center pin and this bore has an opening 9 on the under side of the bolster to permit access to the pin for rotating the pin, as will hereinafter appear.

The center bore 7 of the center filler has a pair of instanding lugs or flanges 10. These lugs of flanges are preferably segmental shaped and disposed diametrically opposite, so that the spaces between them are of substantially the same shape and size. In like manner, the center bore or space 8 of the truck bolster has a pair of segmental shaped instanding lugs or flanges 11.

15 In accordance with my invention, I provide a one-piece center pin C which, in cooperation with the lugs 10 and 11 of the bolsters, is designed to prevent the vertical separation of the car body from the truck during the operation of the car.

20 This center pin is preferably a bar cylindrical in shape and provided at its upper and lower ends with lugs or flanges 12 and 13 respectively. These lugs 12 and 13 are preferably segmental in shape and are disposed diametrically opposite. They 25 are sufficiently less in size so that they will freely pass (Fig. 3) between the lugs 10 and 11 of the bolsters during the assembly and disassembly operation of the car body and truck.

25 In the assembled or normal condition of the 30 car body and truck, as shown more clearly in Fig. 1, the center pin lugs 12 and 13 occupy positions above and below the lugs 10 and 11 of the body bolster and the truck bolster respectively, and thus provide a positive lock between the 35 body bolster and truck bolster against vertical displacement or separation. However, the distance between the under side of the lugs 12 and the upper side of the lugs 13 is sufficiently greater than the distance between the upper side of the lugs 10 and the lower side of the lugs 11 to permit limited longitudinal movement of the center 40 pin for the purpose of locking or unlocking the pin with respect to rotation on its own axis. This locking means consists of small, diametrically 45 opposed lugs 14 which are adapted to engage in recesses 15 in the upper faces of the segmental flanges 11, and these lugs 14 are positioned in the same diametrical line as that of the flanges 12 and 13, so that they do not engage in the recesses 15 until the pin has been rotated on its 50 axis to position the lugs 12 and 13 in vertical alignment with the respect to the lugs 10 and 11. In other words, after the pin has been inserted 55 downwardly in the truck bolster, passing the flanges 13 between the lugs 11 on the bolster, the

pin must then be rotated a quarter turn to bring the lugs 14 into alignment with the locking recesses 15, and this rotation of the pin brings the flanges 13 into alignment with the lugs or flanges 11. When the lugs 14 are thus rotated into registration with the locking recesses 15, the pin is dropped to engage said lugs 14 in the recesses.

Thus, after the pin has been rotated and dropped to engage the lugs 14 and recesses 15, the center pin will be locked against any tendency to rotate incident to the relative movement of the car bolster and car truck during the operation of the car. The center pin is provided with an intermediate circular center flange 16 which is positioned just above the locking lugs 14 and which is substantially of the same diameter as the flange lugs 12 and 13. This intermediate flange rests upon the upper side of the segmental lugs 14 of the truck bolster to support the pin against further downward movement. The intermediate flange occupies a circular recess 17 in the upper side of the bolster, which is sufficiently deep to permit the vertical movement of the pin for engaging or disengaging the locking lugs 14 with respect to the recesses 15 without raising the flange above the top of the bolster. The clearance between the under side of the flange lugs 11 and the upper side of the flanges 13 is likewise sufficient to permit the vertical movement of the pin.

When the car body and truck are to be assembled, the center pin is first inserted downwardly from the upper side of the bolster, the flanges 13 being passed between the segmental flanges 11 of the bolster until said flanges 13 are below the flanges 11. The car body is then lowered until the bolster center filler rests upon the center plate bearing. The flange lugs 12 on the upper end of the pin pass between the lugs 10 during this lowering movement of the car. It is necessary to hold the pin up sufficiently so that the locking lugs 14 will ride upon the top of the flange lugs 11 when the pin is rotated. For this reason, the pin is provided with additional lugs 18 which are disposed at about 90° with respect to the locking lugs 14, so that when the pin is first inserted these lugs 18 will rest upon the flange lugs 11. After the car body has been lowered to position on the center plate bearing, the pin is rotated 90° to align the main locking flanges 12 and 13 with the bolster flanges 10 and 11. During this rotation of the pin, the guide lugs 18 hold the pin up until the locking lugs 14 ride on the lugs 11 and register with the recesses 15, whereupon the pin will drop and engage the lugs 14 and recesses 15 and rest the intermediate flange 16 upon the lugs 11.

In disassembling the car and truck, the reverse handling of the pin takes place, that is, the pin is first raised to release the lugs 14 from the recesses 15, and the pin then rotated 90° to align the flange lugs 12 and 13 with the spaces between the lugs 10 and 11. The car body may then be raised clear of the pin. The ends 19 and 20 of the pin are preferably squared in section to provide suitable engagement for an appropriate wrench or other tool by which the pin may be turned. If the pin is to be rotated or turned at its upper end, access may be had between the center filler and the center sill. If it is to be turned by application of the tool to the lower end of the pin, access is had to this lower end through the opening 9 of the truck bolster.

In the modification shown in Fig. 5, the intermediate flange 16' is sufficiently thicker than the

flange 16 of the previously described structure, so that when the pin is first inserted and the lugs 18' rested upon the lugs 11, it will hold the center plate 5' a fraction of an inch above the center plate bearing on the bolster. When the car body is lowered to the center plate, it still will be that fraction of an inch above its seat on the bolster. The pin is then rotated a quarter turn until the main flange lugs are aligned and the locking lugs 14 reach the recesses 15, whereupon the pin will drop to engage these locking lugs with the recesses. The car body can then follow down with the intermediate flange 16' until the center plate is seated in its bearing. The purpose of this arrangement is to leave less vertical movement of the pin than the height or thickness of the locking lugs 14, so that during the operation of the car, if the pin should bounce, the lugs 14 cannot become disengaged from the recesses and permit the pin to rotate into unlocked position.

In disassembling the car body and truck, the reverse operation occurs, that is, the body is first raised a fraction of an inch off the center plate bearing and the pin can then be raised and rotated into position to free the flanges 12 and 13 from the lugs 10 and 11. In this modified construction, the center plate 5', as shown in Figs. 5 and 6, is provided with an opening 21 which is narrowed sufficiently to overlie the flange 16' so that the plate can be rested on said flange.

In the modification shown in Fig. 7, the intermediate flange 16 is dispensed with and the locking lugs 14 are positioned on the pin below the main flange lugs 13. In addition to this, the truck bolster is provided with an instanding circular flange 22 having the locking recesses 15 formed therein in proper position. In this form, the locking lugs 14 rest upon the flange 22 when the pin is first inserted, and after the car body has been lowered in position and the pin rotated to align the main flange lugs 12 and 13 with the body bolster lugs, the locking lugs ride upon the flange 22 until they register with the recesses 15, whereupon the pin will drop to engage the lugs with these recesses.

I claim:

1. In a structure of the class described, the combination of a body center sill filler having a center pin bore and segmented lugs instanding in said bore, a truck bolster having a space for a center pin and instanding segmental lugs, a center pin having segmental flanges adapted to be passed between the lugs in said bore and space and the pin rotated to engage the flanges with said lugs to lock the center filler and bolster against separation, and additional lugs on said pin projecting into the center pin space in said truck bolster and engageable with bolster lugs therein when the pin is rotated to a position to lock the pin against rotation.

2. In a structure of the class described, the combination of a body center sill filler having a center pin bore and segmental lugs instanding in said bore, a truck bolster having a space for a center pin and instanding segmental lugs, a center pin having segmental flanges adapted to be passed between the lugs in said bore and space and the pin rotated to engage the flanges with said lugs to lock the center filler and bolster against separation, additional lugs on said pin engageable with the bolster when the pin is rotated to a position to lock the pin against rotation, and an intermediate flange on the pin

adapted to bear upon the bolster segmental lugs to support the pin.

3. In a structure of the class described, the combination of a car body bolster and a truck bolster, each having a center bore for a center pin and each having instanding segmental lugs, a center pin having corresponding segmental lugs insertable in said bores between the segmental lugs therein and the pin rotated to position to overlie the segmental lugs in said bores, means on the pin for supporting it in the truck bolster when its segmental lugs are aligned to pass between the lugs in the bolster, and means on the truck bolster cooperating with said supporting means for locking the pin in its rotated position.

4. In a structure of the class described, the combination of a car body bolster and a truck bolster, each having a center bore for a center pin and each having instanding segmental lugs, a center pin having corresponding segmental lugs insertable in said bores between the segmental lugs therein and the pin rotated to position to overlie the segmental lugs in said bores, said truck bolster instanding segmental lugs having locking recesses therein, and locking lugs on said pin adapted to engage the lugs between said recesses prior to rotation of the pin to support the pin in the bolster and to register with and engage said locking recesses in the position in which said pin is rotated for locking the pin against rotation on its axis.

5. In a structure of the class described, the combination of a car body bolster and a truck bolster, each having bores for a center pin, a center pin comprising a cylindrical rod insertable both in said truck bolster bore from the upper side thereof and into the body bolster bore from the under side thereof, instanding lugs in said bores spaced apart circumferentially, corresponding locking flanges on said pin adapted to be passed between the circumferentially spaced lugs in said bores and then rotated into position overlying said lugs in the bores in longitudinal alignment therewith, notches in the upper face of the lugs in the bore of the truck bolster, and locking projections on the pin adapted to engage the truck bolster prior to rotation of the pin and to engage said notches in the rotated position of the pin.

6. In a structure of the class described, the combination of a car body bolster and a truck

bolster, each having bores for a center pin, a center pin comprising a cylindrical rod insertable both in said truck bolster bore from the upper side thereof and into the body bolster bore from the under side thereof, instanding lugs in said bores spaced apart circumferentially, corresponding locking flanges on said pin adapted to be passed between the circumferentially spaced lugs in said bores and then rotated into position overlying said lugs in the bores in longitudinal alignment therewith, notches in the upper face of the lugs in the bore of the truck bolster, locking projections on the pin adapted to engage said notches in the rotated position of the pin, a circular intermediate flange on the pin adapted to bear upon the instanding lugs in said truck bolster bore, said flange and segmental lugs on the pin being spaced apart longitudinally of the pin to permit a limited longitudinal movement of the pin to engage or disengage the locking lugs from the notches.

7. In a structure of the class described, the combination of a car body bolster and a truck bolster relatively rotatable and a center plate bearing between said bolsters, locking flanges in both of said bolsters, a center pin comprising a cylindrical bar having locking lugs at its ends adapted to be inserted in said bolsters beyond said flanges and then rotated axially to overlie the flanges in locking relation thereto, said flanges in said truck bolster having notches in their upper faces and said pin having projections and adapted to register with said notches when the pin is rotated to position, and to engage said notches by the vertical movement of the pin, and a circular flange on the pin positioned to prevent the center bearing plate from seating until the pin has been rotated to position and the pin moved vertically downward to engage the projections and notches.
